(57) **CLAIM**

The ornamental design for a display device for displaying objects, as shown and described.

DESCRIPTION

FIG. 1 is a perspective view of a display device for displaying objects showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIGS. 8, 9, 10 are perspective views thereof, the displayed objects depicted by means of broken lines being for illustrative purposes only and forming no part of the claimed design.

FIG. 10 shows the transparent cover removed for convenience of illustration.
